UNITED STATES PATENT OFFICE.

JOHN HENRY YOUNG, OF KINGSBURY, INDIANA.

BAND-CUTTER AND FEEDER.

SPECIFICATION forming part of Letters Patent No. 625,010, dated May 16, 1899.

Application filed April 18, 1898. Serial No. 678,011. (No model.)

To all whom it may concern:

Be it known that I, JOHN HENRY YOUNG, a citizen of the United States, residing at Kingsbury, in the county of La Porte and State of Indiana, have invented certain new and useful Improvements in Band-Cutters and Feeders; and I do declare the following to be a full, clear, and exact description of the invention, such as will enable others skilled in the art to which it appertains to make and use the same.

The invention has relation to an improved band-cutter and feeder for threshing-machines; and the object is to improve the construction shown in Letters Patent No. 582,712, granted to me on May 18, 1897, whereby after the tie of the bundle is severed and the bundle spread in an even mass this mass will be conducted direct to the threshing-cylinder in a smooth even layer.

With this object in view the invention consists in certain features of construction and combination of parts, which will be herein-after fully described and claimed.

In the accompanying drawings, Figure 1 is a perspective view of my improved band-cutter and feeder, looking from the rear toward the forward end thereof. Fig. 2 is a top plan view. Fig. 3 is a longitudinal sectional view showing the upper and lower conveyer of the cylinder-feed in operative position. Fig. 4 is a similar view showing the upper conveyer of the cylinder-feed elevated and the lower conveyer of the cylinder-feed swung down and back in order to repair or clean the parts as well as to make room for the repair of the threshing-cylinder. Fig. 5 is a longitudinal sectional view through the crank-pin and the universal coupling. Fig. 6 is a vertical sectional view through the journal-box of the cutter-shaft. Fig. 7 is a detail perspective view of one of the slot-closing plates. Fig. 8 is a similar view of one of the saddle-boxes. Fig. 9 is a cross-sectional view taken through the rear end of the machine, the divide-board, and feed-boards. Fig. 10 is a detail perspective view of one of the roller-supporting bars. Fig. 11 is a longitudinal sectional view. Fig. 12 is a detail perspective view of one of the bars that support the lower conveyer of the cylinder-feed, and Fig. 13 is a detail perspective

view of one of the slats of the lower conveyer of the cylinder-feed.

In said drawings, 1 denotes the frame of the feeder, which consists of side pieces 2, 55 the front end piece 3, and the bottom 4. The bottom and side pieces intermediate their ends are separated and are connected together by hinges 5, whereby the forward end of the frame may be swung under the bottom. 60

66 denote the rollers of the main bundle-conveyer, and 7 denotes the slatted conveyer adapted to travel around said rollers and feed the grain from the forward to the rear end of the machine. 65

8 denotes a roller journaled to the extreme forward end between the side pieces and projecting slightly above the upper edge of the end piece 3. This roller serves to prevent the bundle hanging or rubbing against the 70 upper edge of the end piece 3, and thus materially assists in the feeding of the bundle to the conveyer.

9 denotes the divide-board, the rear end of which is connected to standards 10, that fit 75 in brackets on the outside of the side pieces of the frame, and the forward end of which has a post secured to it and fits in a bracket secured to the end piece 3 of the frame.

11 denotes the cutter-shaft, provided with 80 disk cutters 12. This shaft is journaled in boxes 13, secured to posts 14, and these boxes are made adjustable by the bolts 15, so as to raise or lower the edges of the cutting-disks with respect to the bottom of the frame. This 85 shaft has a fly-wheel 16 on one end and a band-pulley 17 on the other end.

18 denotes guide-wings, which are secured to the side pieces and extend forwardly and outwardly around the standards that support 90 the rear end of the divide-board, thus serving to prevent the grain fed over the inclined feed-tables 19 from hanging or straddling the said standards in its progress along the bottom of the machine. 95

20 denotes guide-rods secured to the side pieces of the frame above their upper edges, and 21 denotes rake-heads having a lateral sliding engagement on said rods at right angles to the path of movement of the main conveyer. These heads are provided with tines that project downwardly to a point slightly 100

above the main conveyer and serve to spread the grain after the band has been severed by the cutters in an even mass across the bottom of the machine.

5 22 denotes bell-crank levers connected to posts 23 and 24, and 25 and 26 denote links connecting the rake-heads to one of the arms of each of the bell-crank levers. 27 denotes a link connecting the other arms of the bell-crank levers, and 28 denotes a pitman connecting one of the arms of the bell-crank lever with the wrist-pin 29 in the crank-wheel 30, secured to one end of a fly-shaft 31, having at its opposite end a fly-wheel 32. This 15 crank-wheel is provided in its face with apertures 33, arranged at different points from the axis of the wheel, whereby the wrist-pin may be adjusted so as to vary the amount of throw of the pitman. The pitman has a universal connection with the wrist-pin by a coupling 34, which receives a ball 35 of the wrist-pin and forms a ball-and-socket joint. The extreme outer end of the wrist-pin is preferably squared, so as to permit of its being 25 removed from the crank-wheel by a wrench, the other end of the pin being screw-threaded to engage the screw-threaded holes in the crank-wheel. One end of the rear roller that supports the main conveyer is extended and 30 is provided with a drive-pulley 36, which may be geared with any movable part of the threshing-machine. 37 denotes a pulley fixed to said shaft and connected with a pulley on the end of the cutter-shaft by a crossed belt 38 35 and by which the cutter-disks are rotated. Depending from the rear ends of the side pieces of the frame are wings or extensions 39, between which are journaled rollers 40, that support the endless conveyer 41, which 40 is the lower conveyer of the cylinder-feed. This conveyer 41 is provided with slats 42, having on their forward edges metallic strips 43, the upper edges of which project slightly above the upper surfaces of the slats, and are 45 preferably formed with saw-teeth 44. These rollers 40 are journaled between the downwardly-depending wings in a novel manner, which I will now proceed to describe.

45 denotes a bar having at its rear end apertures, in which are fitted journals 50 of the rear roller, and having at its forward end apertures 51, in which are fitted journals 52 of the forward roller.

53 denotes a lever having intermediate its 55 ends an aperture 54, in which are fitted journals of the forward roller, and having its forward end pivoted to a stud 55 and held in place by a nut 56.

57 denotes an inclined slot formed on the 60 lower edge of the wings and terminating in an oblique bearing-slot 58.

59 denotes a set-screw that works through a hole 60 in the rear end of the pivoted lever and into a hole 61 in the bar. When it is desired to lower or swing the conveyer down for any purpose, these screws are removed and the outer ends of the lever swung downward.

This movement will draw the axis of the rear roller of the conveyer forwardly to disengage it from its bearing-slot and allow it to drop 70 from the inclined slot, as shown in the drawings. In elevating the belt on the conveyer into position the axis of the roller is raised up into the inclined slot, and when it comes opposite the bearing-slot the rear end of the 75 lever is elevated, thus causing the bar to be forced longitudinally, and thereby moving the axis of the roller into the bearing-slots in the wings. The screws are now screwed home, and the rollers of the lower conveyer of the 80 cylinder-feed are securely held in position.

62 denotes a pan arranged below the lower conveyer of the cylinder-feed. The forward end of this pan is pivoted upon a rod 62', and the rear end is provided with a board 63, that 85 is adapted to project under the edge of the feed-table 64 of the threshing-machine and abut against a shoulder 65. This pan is held in this position by a removable rod 66, fitted in eyes 67, secured to the under edges of the 90 wings. 68 denotes slot-coverers that are adapted to cover the inclined slots formed in said wings. These coverers have laterally-projecting arms 69, formed with slots 70, and bolts 71 are employed for adjusting these coverers to 95 the sides of the wings opposite the slots.

72 denotes the upper conveyer of the cylinder-feed. This conveyer consists of the endless belts 73, connected together by slats 74.

75 denotes bars secured to the side pieces of the frame, and are provided at their lower ends with segmental slots 76 and at their upper ends with adjustable boxes 77. The boxes 77 support a shaft 78, provided with rollers 79, around which the belts pass, and the curved 100 slots receive the journals 80 of a roller 81, around which the belt also passes. The journals 80 of the rollers 81 have removable saddle-boxes 81', connected by coiled springs 82 to the wings of the frames. These springs tend 110 to draw the rear end of the upper conveyer downward and hold it in contact with the grain.

The shaft 78 is provided with a sprocket-wheel 83, that is geared with the sprocket-chain 84, and a chain-tightener 84' is arranged below the sprocket-wheel and is journaled by a stud secured to an adjustable bracket 85. This bracket may be shifted and held in adjusted position by a set-screw 86, so that the 115 chain may at all times be adjusted to compensate for wear.

87 denotes a sprocket-wheel on the end of the roller 8, and 88 denotes a similar sprocket-wheel on the end of the roller 6. A chain 89 125 connects these two sprockets and imparts the motion of the roller 6 to the roller 8.

The direction of movement of the revolving parts of the machine is indicated by the several arrows, and a detail description of the 130 operation, it is thought, will not be necessary.

In operation the bundles of grain are fed to the forward end of the main conveyer over the end piece 3 and the roller 8, which serves

to assist in holding the bundle onto the conveyer. As the bundle is drawn rearward by the conveyer its band is severed by the rotary knives, and the grain in this condition is then presented to the rake-tines, which, moving transversely across the path of travel of the conveyer, evenly spread and distribute the grain upon said conveyer. In this condition the grain is delivered to the conveyers 5 constituting the thresher-feed, and in order to conduct the grain direct to the cylinder in its spread condition is the object of this cylinder-feed. The grain falls upon the lower conveyer and is fed between the diverging 10 rear ends of said conveyers direct to the mouth of the threshing-cylinder. The upper conveyer of the cylinder-feed, owing to its 15 spring action, will prevent the clogging of the grain and the consequent stopping of the machine.

Having thus described my invention, what I claim, and desire to secure by Letters Patent, is—

1. In a band-cutter and feeder, the combination with the main frame having at its rear end two depending wings provided with slots projecting upward from their lower edge and terminating in bearing-slots arranged at an angle to the first-named slots, a lever having 25 one end pivoted to stud-shafts and having intermediate its ends bearing-apertures to re-

ceive the journals of the forward roller of the lower conveyer, a bar having at its forward end bearing-apertures to receive said journals, and having at its rear end bearing-apertures to receive the journals of the rear roller of said lower conveyer, and means for locking the bar to the lever, substantially as set forth. 35

2. In a band-cutter and feeder, the combination with the main frame having at its rear end two depending wings provided with slots projecting upward from their lower edge and terminating in bearing-slots arranged at an angle to the first-named slots, a lever having 40 one end pivoted to stud-shafts and having intermediate its ends bearing-apertures to receive the journals of the forward roller of the lower conveyer, a bar having at its forward end bearing-apertures to receive said journals, and having at its rear end bearing-apertures to receive the journals of the rear roller of said lower conveyer, means for locking the bar to the lever, and adjustable slot-closers, substantially as set forth. 45

In testimony whereof I have hereunto set my hand in presence of two subscribing witnesses.

JOHN HENRY YOUNG.
